UNITED STATES PATENT OFFICE.

CARL E. LINDEN AND GEORGE H. LANGEN, OF CINCINNATI, OHIO, ASSIGNORS TO THE CINCINNATI PLANER COMPANY, OF CINCINNATI, OHIO, A CORPORATION OF OHIO.

CLAPPER BOX FOR PLANERS.

Original application filed February 16, 1922, Serial No. 537,061. Divided and this application filed April 8, 1925. Serial No. 21,656.

Our invention relates to the boxes that carry the tool upon the cross rails of metal planers, the same being known as clapper boxes, and this application is a division of our 5 copending application Serial No. 537,061, filed February 16, 1922.

In metal planers the tool carrying heads must be shifted to various angles, and hence are of pivotal support, and are held in place 10 by suitable clamping devices. In the adjusting of the heads the boxes are naturally, first free from the clamps, and in this operation the boxes will often swing around, due to being overbalanced and the parts thereof or the 15 tools strike the workman and injure him, or strike a projecting part of the work and mar it.

It is the object of our invention to provide a 20 clapper box or tool head which has a rocking motion, and a full clamping element to hold it tightly in adjusted position, but in which the factor has been introduced of limiting the rocking motion by a stop pin or pins, so arranged that the devices cannot revolve 25 clear around, but only sufficiently to take care of all adjustment.

We accomplish our objects by that certain 30 construction and arrangement of parts to be hereinafter more specifically pointed out and claimed.

In the drawings:

Figure 1 is a perspective view of a tool carrying device, such as is mounted on a planer cross rail.

Figure 2 is a front elevation of the clapper box and clamp.

The usual slide 1 is illustrated, on which is pivoted at 2, the tool block 3. Held onto the slide by bolts 3^a is the clamp 4.

The tool block or clapper box has a web 5 which extends up under the overhanging portion 6 of the clamp, and the shoulder 7 defining the main body of the clamp from the overhanging flange thereof, is curved, as is the top of the web 5 so as to permit the box to rock on its pivot when the clamp is slightly relaxed.

The clamping engagement is effected by tightening the clamp down by means of the

bolts 3^a, which presses the flange 6 of the 50 clamp against the web 5 of the box.

In one form of the device a space is left between the shoulder 7 of the clamp and the top of the web 5, and the stop devices to prevent the box revolving around when freed, 55 are located in this space. These stop devices are in the form of pins or lugs. On the left of the top of the web is set a pin 8, which engages a pin 9 on the right of the shoulder 7. On the right of the top of the web is a pin 10, which 60 engages a pin 11, on the left of the shoulder 7. The pins 8 and 11, and the pins 9 and 10, lie alongside of each other and do not engage each other.

It will be noted that we thus provide for the 65 safety factor, which we have heretofore noted, without reducing the force of the clamp, or its release by a slight relaxation of the bolts.

Having thus described our invention, what 70 we claim as new and desire to secure by Letters Patent, is:—

1. In a metal planer, the combination with the mounting member of a tool head, of a clapper box mounted thereon, and a clamp having 75 an arc shaped shoulder and a flange on said shoulder extending downwardly over the upper edge of said clapper box, said shoulder and edge being formed on an arc with clearance between said shoulder and edge, and 80 means extending from said shoulder and edge providing stops for said clapper box at the limits of its swing.

2. In a metal planer, the combination with the mounting member of a tool head, a clapper box mounted thereon, a clamp mounted on the support, and having an arc-shaped shoulder and a flange projecting from said shoulder downwardly over the upper edge of the clapper box, said shoulder and edge of the 90 clapper box being formed on an arc with clearance between said shoulder and edge, and stop pins located on the said edge and shoulder and projecting into each other's paths to constitute stops for the clapper box at the two 95 ends of its full swing.

CARL E. LINDEN.
